[57] CLAIM

The ornamental design for a cup or similar article, as shown and described.

DESCRIPTION

FIG. 1 is a front elevational view of a cup or similar article showing my new design;

FIG. 2 is a left-side elevational view thereof;

FIG. 3 is a sectional view taken along lines 3—3 of FIG. 1;

FIG. 4 is a perspective view thereof;

FIG. 5 is a top plan view thereof; and

FIG. 6 is a right-side elevational view thereof.

The rear elevational view is substantially an unadorned cylindrical shape as seen in the left portion of the cup in FIG. 2. The bottom of the design is flat and unornamented.

FIG. 1

FIG. 2

FIG. 3

FIG. 4

FIG. 5

FIG. 6
